AIR CONDITIONING SYSTEM FOR
RAILROAD CARS

Willis H. Carrier, Essex Fells, N. J., assignor, by
mesne assignments, to Carrier Corporation,
Newark, N. J., a corporation of Delaware

Application February 21, 1930, Serial No. 430,210

6 Claims. (Cl. 62—117)

This invention relates to methods of and means for cooling and conditioning enclosures, more particularly railroad cars.

The general object of the invention is to provide a system of air conditioning adapted to be installed in a railroad car of conventional design. Inasmuch as the requirements of operation and the traffic load of a railroad car are rarely constant, and in view of the mobile character of railroad carriages, the problem of air conditioning this equipment presents difficulties not ordinarily encountered. Thus, for example, the usual water supply available in the air conditioning of fixed plants is obviously not to be had for use in railroad cars. As a result, if water is to be used in the system, it must be maintained and circulated in substantially closed circuits. No regular feed can be provided nor any additions be made except at periodic intervals for purposes of replenishment.

A feature of the invention resides in the provision of an air conditioning system having a plurality of substantially closed water circuits, one of which is used for the conditioning of air and another of which is itself changed in character by the action of a supply of air. The water used for conditioning air is refrigerated by means arranged to be located in any suitable space in the car. The water is routed through a conditioner designed to intake outside air and to circulate return air in a course through or around the conditioner.

Another feature of the invention, therefore, embraces the design and use of a conditioner served by a plurality of air sources of different character. Control instruments are provided so that the volumes of outside and return air may be suitably proportioned to make allowance for variations in outside conditions and in refrigerating load.

Another object of the invention is to provide a cooling tower of a design suitable for economical installation in an area ordinarily not used for passenger seating accommodation and whose efficient operation is not dependent upon a continuous supply of water from an outside source. Applicant has designed the cooling tower so that its operation is a function of outside air conditions and its efficiency unimpaired regardless of fluctuations in said conditions. The cooling tower may be of a design similar to that of the conditioner used in the system, and hence manufacture of conditioning and cooling tower units is simplified and rendered relatively economical. Since the operation of the cooling tower requires

an outside air source, provision is made for routing desired large quantities of outside air through the cooling tower. Provision is also made for utilizing return air also, if operating expedience so demands.

A further feature of the invention, therefore, resides in the arrangement of a duct system in combination with a cooling tower, whereby a source of water routed to the cooling tower may be reduced in temperature and changed in character to a substantially fixed degree by contact with controlled amounts of air whose character may be fluctuating.

Further objects and features of the invention covering the arrangement and design of component parts used therein, and resulting in maximum efficiency and economy of installation and operation will be more apparent from the following description of one form of the invention, to be read in connection with the accompanying drawing, in which—

Fig. 1 is a diagrammatic illustration of an air conditioning system adapted for use in a railroad car;

Fig. 2 is a sectional view, to a larger scale, of a unit designed to be used as a conditioner or as a cooling tower; and

Fig. 3 is a prospective fragmentary view of a portion of a car, showing an illustrative installation of a cooling tower and its associated ducts.

Considering the drawing, similar designations referring to similar parts, numeral 4 refers generally to the combination of apparatus shown in Fig. 1 and the relation of the various components to each other. The system includes a compressor 5, which may be used for any desired refrigerant, condensers 6, evaporators 7a and 7b, expansion valve 8, air conditioning unit 9, cooling tower unit 10, pumps and auxiliary motors 11, 12 and the usual connecting lines and accessories ordinarily required for completing and assembling the system in an operating arrangement.

In the layout illustrated, any suitable refrigerant, such as ammonia, may be employed and the refrigerant circuit illustrated may be traced in a course including compressor 5, condensers 6, expansion valve 8, in parallel through coils within evaporators 7a and 7b and back to the compressor.

The water circuit for the conditioning unit is substantially closed and follows a course, including pump 12, around the coils of evaporator 7a, through the air conditioning unit, within and around the coils of evaporator 7b, and back to the pump.

The condenser water circuit proceeds from pump 11 to the condensers, then to the water tower unit 10 and back to the pump.

The pumps may be suitably associated with the traction equipment of the car and hence will be operated whenever the car is in motion. It is obvious, of course, that any desired overflow device may be provided as well as connections for replenishing the water supply and otherwise servicing the apparatus.

Since the system is merely shown in diagrammatic form for illustrative purposes only, the general scheme of assembly and operation is indicated without including the numerous details usually included in the practical application and installation of the system.

In Fig. 2 unit 13, corresponding to air conditioning unit 9 of Fig. 1 includes an outer liquid reservoir 14, inner sump 15, pump 16 and auxiliary spray device 17, the pump being mounted on shaft 18 of motor 19. The shaft also mounts a fan 20. Eliminators 21, are provided for removing entrained moisture, prior to discharge of the air from the unit to distributing duct 22. Preferably, the unit is located at one end of the car. While the unit preferably extends substantially the height of the car, it is evident that it may be suitably arranged in any desired manner, preferably so that the usual water fountain and lavatory facilities may still be provided. The unit 13 is preferably positioned adjacent window 23 of the car. Intake opening 24 of the conditioner is connected to the window opening by a suitable duct or partition, so that air from outside may be drawn through the window and within the conditioner by the suction of fan 20. Intake opening 25 of the conditioner is arranged to draw air from the car through the conditioner whereas recirculating opening 26 draws air from the car within the casing in a source by-passing the sprays. In the operation of the conditioning equipment, the pump and fan will be revolved by motor 19. The pump will draw water supplied to sump 15 and eject it in the form of spray through the nozzles of device 17 due to the centrifugal action. The water from the spray will drop to reservoir 14 and thence be removed from the conditioner. The outside air and return air will be routed through the sprays by the fan and discharged to distributing duct 22. The condition of the air after it leaves the sprays, regardless of whether it was originally outside or return air, is substantially the same. As the recirculating opening 26 allows air to enter, this conditioned air will be mixed with recirculated air prior to discharge.

The fresh air opening may be hand controlled, or, if desired, the opening may be equipped with louvers under the control of a thermostat. Similarly, openings 25 and 26 may be hand controlled or may be equipped with dampers whose operation is under automatic control. Thus, the fresh air inlet will be opened more widely as the number of people in the car increases. The return inlet 25 may be opened when the temperature in the car tends to rise; while on the other hand if the temperature tends to fall, opening 25 will be closed to a greater degree and inlet 26 opened. The recirculating air through inlet 26 will serve to reheat the conditioned air, thus raising the dry bulb temperature and lowering the relative humidity of the final mixture. The controls are not illustrated since applicant does not confine himself to any type of control, but it is understood that any desired devices of positive or

graduated type may be utilized for temperature and humidity control purposes.

In Fig. 3 a duct system is provided for removing the air routed through cooling tower 13a. In this arrangement outside air from window 23 will be routed through the cooling tower in the same manner as illustrated in Fig. 2. If desired, return air from the car through inlet 28, will also be intaken and routed through the cooling tower in combination with the outside air. The condenser water will thus be reduced in temperature due to its intimate contact in the form of spray with the large volumes of air passed through the cooling tower. If all outside air is used, the water will be cooled to a point approximating the outside wet bulb temperature. If return air is also used, the wet bulb temperature of the mixture will be the gauge of the cooling effect on the water. It is found that the differential in temperature between the water at the condensers and its condition at the cooling tower is substantially constant regardless of outside conditions. In view of the necessity for routing large volumes of air through the tower, and for reducing flow resistance to a minimum, applicant provides outlets 29 and 30 at the upper end of the service and toilet space on one side of the car and outlet 31 at the other side of the car. The duct to outlet 31 is along the roof of the car in the vestibule space and hence inconspicuous. The appearance of the car is left preserved and the interior space is wholly reserved for its usual passenger accommodation purposes.

While applicant is illustrating the assembly of parts and the operation of the system as well as that of the conditioner and cooling tower, in certain and definite ways, it should be understood that the illustrations described herein are merely deemed representative. Any analogous means for carrying out similar objects are deemed within the purview of the invention.

Having described my invention, what I claim as new and desire to secure by Letters Patent, is:

1. In an air conditioning system for a railroad car, condensing equipment for effecting heat exchange from a refrigerant used in the system, a cooling tower having a reservoir in the bottom thereof, a water circuit including said condensing equipment and said reservoir, means for spraying water from said reservoir downwardly through said tower, another reservoir in the bottom of said tower for receiving the spray, an outlet from said other reservoir leading to the condensing equipment, said reservoirs being located one within the other in the cooling tower.

2. The method of conditioning the air in a passenger vehicle, which consists in drawing the air into a unit, passing the air through a cold water spray in said unit to remove all foreign matter therefrom, and reducing the temperature of the air, regulating its moisture content, all of which is accomplished in said unit, and then distributing the conditioned air at a plurality of points into the space occupied by passengers in the said vehicle, and then cooling the said water for reuse and returning it to the spray.

3. The method of conditioning the air in a passenger vehicle, which consists in drawing the air into a unit, passing the air through a cold water spray in said unit to remove all foreign matter therefrom, and reducing the temperature of the air, regulating its moisture content, and eliminating the entrained water from the air, all of which is accomplished in said unit, and then distributing the conditioned air into the space

occupied by passengers in said vehicle, removing the heat units from said spray water, and returning said cooled water to said spray, then dissipating these heat units in a cooling tower.

5. The method of conditioning air in a passenger vehicle, which consists in drawing air into a unit, passing air through a cold water spray in said unit to remove all foreign matter therefrom and reducing the temperature of the air, regulating its moisture content and eliminating the entrained water from the air, all of which is accomplished in said unit, distributing the conditioned air into the space occupied by passengers in said vehicle, removing heat units from said spray water, and returning said cooled water to said spray.

10. In an apparatus for air conditioning a railroad car, an air conditioning casing, a first inlet in said casing, means for admitting air from the outside atmosphere to said casing through said first inlet, a second inlet for admitting air from the interior of said car to the interior of said casing, a fan for drawing upwardly through said casing air intaken through said first and second

inlets, means for creating a spray of water in the path of said air intaken through said first and second inlets, a third inlet for admitting to said casing air from the interior of said car, said third inlet being located above said spray-creating means, whereby air intaken through said third inlet bypasses said spray, and means for supplying air intaken through all of said inlets to said car.

15. A heat transfer device including means forming a tower, means forming a reservoir proximate the bottom of said tower, means for supplying liquid to said reservoir, means for spraying liquid drawn from said reservoir downwardly through said tower, means for routing gas through said tower in contact with said sprayed liquid, means forming another reservoir within said tower and proximate the bottom thereof for receiving sprayed liquid, said reservoirs being located one within another and being segregated from each other, and means for withdrawing liquid from said second-mentioned reservoir.
